WEAVING APPARATUS

Joseph E. Arena, United States Army;
Hammonton, N. J.

Application February 21, 1946, Serial No. 649,447

6 Claims. (Cl. 28—1)

(Granted under the act of March 3, 1883, as
amended April 30, 1928; 370 O. G. 757)

1

The invention described herein may be manufactured and used by or for the Government for governmental purposes, without payment to me of any royalty thereon.

This invention relates to weaving apparatus, and more particularly to an apparatus for weaving narrow strips or garlands into camouflage nets, although not limited thereto.

In the art of camouflage, nets are draped over heavy weapons, vehicles, stores and other bulky objects, the construction and appearance of the net being such that the same blends into the surrounding area. It has been found that for certain purposes, such as those of a combat area, cloth garnishing has been most practical. The net itself is a simple arrangement of suitably spaced parallel longitudinal strands intersected at suitable intervals by parallel cross-strands. There are a number of materials which may be used for net-garnishing, such as chicken feathers, steel wool, Spanish moss between layers of chicken wire, glass wool, patch-and-strip garnishing, etc., using natural and artificial materials. Most frequently the garnishing material takes the form of cloth garlands of strands, usually in the form of relatively narrow woven strip, and the task of weaving the same into the net (or base fabric) is tedious at best. It is not practicable, and sometimes not possible, to predict the desired combinations of colors and patterns to be provided by the garlands; and for this reason the garlands cannot be incorporated in the net at the time of its manufacture. It is therefore necessary to perform this operation separately and subsequently. Whether this operation takes place in the factory or at the combat area, it is extremely time-consuming and tiresome.

It is among the objects of the present invention to provide a weaving apparatus which, while adapted for other uses, is particularly adapted to semi-automatically garnish camouflage nets, whereby time and man power is greatly conserved.

Another object is the provision of an apparatus of the type described which is simple and inexpensive to manufacture, operate and maintain.

Still another object is the attainment of the foregoing by an apparatus which may also be operated to shear the garland in such manner as to leave it in place.

A further object is the provision of an apparatus of the class described which may be operated in speedy fashion over a long period of time with but a minimum of fatigue.

The invention, then, comprises the features hereinafter fully described, and as particularly pointed out in the claims, the following description and the annexed drawings setting forth in

2 detail a certain illustrative embodiment of the invention; this being indicative of but one of several ways in which the principles of the invention may be successfully employed.

5 In said drawings:

Figure 1 is a perspective of the apparatus of the present invention;

Figure 2 is a side elevation;

10 Figure 3 is a perspective illustrating in detail the upper and lower elongate strips between which the strand is fed;

Figure 4 is a fragmentary detail, partly in section, of the forward end of the apparatus;

15 Figure 5 is an elevational view on the line 5—5 of Figure 2;

Figure 6 is a fragmentary plan on the line 6—6 of Figure 2;

Figure 7 is a perspective illustrating the function of the apparatus; and

20 Figure 8 is a fragmentary elevation, partly in section, of the forward end of the apparatus.

Referring more particularly to the drawings, the weaving apparatus of the invention comprises a horizontally disposed oblong frame which is made up of a pair of parallel longitudinal members 2 and right-angularly disposed end members 3 which connect the longitudinal members adjacent one of their extremities. If desired, the longitudinal members 2 and the end member 3 may take the form of standard structural elements, for example, angle irons, etc.

25 A pair of diagonal members 4 are secured to and extend upwardly from the longitudinal members 2 and project beyond the adjacent ends of the latter. The upper ends of these diagonally upwardly extending members 4 terminate in handle members 5. Vertical bracing members 6 extend between, and connect, the diagonally upwardly extending members 4 with the longitudinal members 2 of the horizontally disposed oblong frame.

30 Immediately below each of the vertical bracing members 6 there is mounted a wheel 8 for supporting the adjacent end of the horizontally disposed oblong frame. Referring to the opposite, or forward, end of the oblong frame, the end member 3 carries an inwardly extending horizontal shaft 11 on which there is pivotally mounted a yoke 12 carrying a normally horizontal spindle 13 on which there is rotatably mounted a pair of relatively small wheels 14.

35 The elements thus far described, form a wheeled truck or carriage which may be efficiently moved about by utilizing the handle members 5 of the diagonally upwardly extending members 4.

40 Disposed immediately below the vertical bracing members 6 is a horizontal apron 18 which extends between the parallel longitudinal members 2, and is mounted for swinging movement

with respect thereto. This apron 18 carries a pair of spaced horizontal strips 20 which are disposed between, and extend in parallelism with, the longitudinal members 2, to terminate adjacent to, but in spaced relationship from, the yoke 12 carrying the relatively small wheels 14.

The apron 18 carries a pair of aligned and widely spaced vertical supports 22 each of which carries an anti-friction roller 23. A horizontally disposed slidable plate 24 is supported by the 10 anti-friction rollers 23 and is free to move forwardly and rearwardly of the oblong frame.

The horizontally disposed slidable plate 24 carries a pair of strips 25 which are disposed over the previously described spaced horizontal strips 20; and the forward ends of the strips 25 converge onto and make contact with the corresponding portions of the said strips 20 as shown in Figure 3 of the drawings. The remaining portions of the strips 25 extend angularly away from the strips 20 to provide passages therebetween; and the edges of the forward ends of the strips 25 are serrated, as shown at 25a. The purpose of such construction and arrangement will shortly appear.

The diagonal members 4 support a horizontal shaft 28 which is disposed above and transversely of the longitudinal members 2. Suitable lever-and-link systems connect the slidable plate 24 with the shaft 28 and the latter with an operating handle 30 which is disposed conveniently adjacent the right-hand handle member 5, as shown in Figure 1.

The forward edge of the horizontal apron 18 (which is mounted at its ends for swinging movement) carries a forwardly projecting lever 31 to which there is attached an operating cable 32. The other end of the operating cable 32 connects with an operating lever 33 which is disposed adjacent to the left-hand of the handle members 5.

Referring more particularly to Figure 3, the forward end of each of the pair of lower strips 25 carries a short hingedly mounted extension 35 which is capable of upward angular movement with respect to a horizontal plane.

The side edges of the hingedly mounted extensions 35 and the correspondingly adjacent portions of the lower strips 20 are provided with upwardly extending integral flanges 35a and 20a, respectively, which overlap at their adjacent ends. The upwardly extending integral flanges 20a of the lower strips 20 are tapered inwardly, as at 20b, to substantially the upper surfaces of said strips. The upwardly extending integral flanges 35a of the hingedly mounted extensions 35 taper outwardly thereof from a height which is substantially that of the corresponding flanges 20a of the contiguous lower strips 20 to the plane of the upper surfaces of the said extensions as shown at 35a. Preferably, too, the forward extremities of the extensions 35 are complementarily beveled to provide for easy insertion of the said extensions under the cross-strands of the net, the manner and purpose of which will appear immediately hereinafter.

At the inner ends of the upwardly extending integral flanges 35a of the extensions 35 there is formed a vertical protuberance or ear 37 for the purpose of enabling a cross-strand riding thereover to elevate the said extensions whereby they will be permitted to ride over the next parallel cross-strand; provided, of course, that the latter is not too closely or too distantly spaced. Thus, the extensions will ride over and under the parallel cross-strands in alternating relationship.

Referring to Figure 2, the vertical bracing members 6 carry a transverse shaft 40 which is adapted to support a pair of rotatable reels 41 of the strands to be woven through the cross-strands of the net or base fabric. For illustrative purposes, the strands 42 are shown as of garnishing material for camouflage nets, and take the form of relatively narrow woven strips.

From its rotatable reel 41, each of the strands 42 (i. e. relatively narrow woven strip) is fed downwardly, then over a transversely extending guide 43; then horizontally forward into and through the space between the adjacent pair of upper and lower strips 25 and 20 respectively. As the strands 42 pass from between the forward ends of their respective lower and upper strips, they extend over the upper surfaces of the hingedly mounted extensions 35 on the said lower strips.

20 A stationary shear blade 45 is carried by one of the longitudinal frame members 2 at a point which is forward of the hingedly mounted extensions 35 on the forward ends of the lower strips 20. Cooperating with the stationary shear blade 45 is a pivotally mounted horizontally movable shear blade 46 which is actuated by an operating cable 47. The other end of the operating cable 47 is connected to an operating handle 48 which is mounted adjacent the handle member 5 of the 25 right-hand diagonal member 4.

In operation:

A camouflage net X is stretched out on a relatively flat surface and the machine of the invention is moved to the desired point on the net 35 while the operator squeezes the lever 33 to partially rotate the shaft 28 and elevate the forward edge of the horizontal apron 18. This elevates the bottom strips 20 and the upper strips 25 which ride thereon; and prevents the said bottom strips from dragging on the ground.

40 Next, the hingedly mounted extensions 35 on the lower strips 20 are aligned with the longitudinal rows of the net X; the lever 33 is released to lower the lower strips 20; and by the use of 45 the handle members 5 the machine is pushed forward. In moving the ears 37 on the side flanges 35a of the hingedly mounted extension 35 on the lower strips 20 catch the cross-strands of the net and cause the said extensions 35a to rise over alternate cross-strands. The machine is moved as far as it is desired to garnish the net X and is then stopped. The operating handle 30 is operated to partially rotate the shaft 28, move the slidable plate 24 forwardly, and thereby impart forward movement to the upper strips 25. This forward movement of the upper strips 25 permits the serrations 25a on the forward ends to catch the strands 42 and project them forwardly over the stationary lower strips 20. The machine is then backed up slightly so that the wheels 14 rest on the projected ends of the strands 42 and hold them against withdrawal thereof from the net as the machine is moved rearwardly to the point at which the operation was begun. During this rearward movement of the machine the strands 60 42 are drawn from between the forward ends of the lower and upper strips. At the end of the rearward movement the operator again squeezes the lever 33 to elevate the bottom strips 20 and the upper strips 25 to a height at which the body portions of the strands 42 are in the path of the 65 movable shear blade 46. The operating handle 48 is then moved to actuate the movable shear blade 46 and sever the adjacent portions of the strands 42.

In the foregoing manner, then, the strands 42 are interwoven into the net X. Securing of the strands 42 in the interwoven relationship may be accomplished in any suitable manner.

Having thus described my invention, what I claim as new and wish to secure by Letters Patent is:

1. Apparatus for weaving a strand into a substantially horizontally disposed open-mesh cross-strand fabric comprising a wheeled carriage adapted for movement over said fabric, an elongate strip adapted to assume a substantially horizontal position in close proximity to said fabric, a deflectable extension on one end of said elongate strip, a second elongate strip disposed above and in substantial parallelism with said first-named strip whereby the strand to be woven may be inserted between said strips, the upper strip being disposed to converge upon and engage the inserted strand at a point which is adjacent the deflectable extension on the lower strip, and means on said deflectable extension for engagement by the cross-strands of the fabric to impart a weaving motion to said extension during the unitary longitudinal movement of the upper and lower strips with the wheeled carriage.

2. Apparatus for weaving a strand into a substantially horizontally disposed open-mesh cross-strand fabric comprising a wheeled carriage adapted for movement over said fabric, an elongate strip adapted to assume a substantially horizontal position in close proximity to said fabric, a deflectable extension on one end of said elongate strip, a second elongate strip disposed above and in substantial parallelism with said first-named strip whereby the strand to be woven may be inserted between said strips, the upper strip being disposed to converge upon and engage the inserted strand at a point which is adjacent the deflectable extension on the lower strip, means for enabling the longitudinal sliding movement of the upper strip with respect to the lower strip to thereby feed the forward end of said strand over said deflectable extension, and means on said deflectable extension for engagement by the cross-strands of the fabric to impart a weaving motion to said extension during the unitary longitudinal movement of the upper and lower strips with the wheeled carriage.

3. Apparatus for weaving a strand into a substantially horizontally disposed open-mesh cross-strand fabric comprising a wheeled carriage adapted for movement over said fabric, an elongate strip adapted to assume a substantially horizontal position in close proximity to said fabric, a vertically deflectable extension on one end of said elongate strip, a second elongate strip disposed above and in substantial parallelism with said first-named strip whereby the strand to be woven may be inserted between said strips, the upper strip being disposed to converge upon and engage the inserted strand at a point which is adjacent the deflectable extension on the lower strip, means on said deflectable extension for engagement by the cross-strands of the fabric to impart a weaving motion to said extension during the unitary longitudinal movement of the upper and lower strips with the wheeled carriage, and means for elevating and lowering the forward end of the lower strip with respect to the wheeled carriage.

4. Apparatus for weaving a strand into a sub-

stantially horizontally disposed open-mesh cross-strand fabric comprising a wheeled carriage adapted for movement over said fabric, an elongate strip adapted to assume a substantially horizontal position in close proximity to said fabric, a vertically deflectable extension on one end of said elongate strip, a second elongate strip disposed above and in substantial parallelism with said first-named strip whereby the strand to be woven may be inserted between said strips, the upper strip being disposed to converge upon and engage the inserted strand at a point which is adjacent the deflectable extension on the lower strip, means for enabling the longitudinal sliding movement of the upper strip with respect to the lower strip to thereby feed the forward end of said strand over said deflectable extension, means on said deflectable extension for engagement by the cross-strands of the fabric to impart a weaving motion to said extension during the unitary longitudinal movement of the upper and lower strips with the wheeled carriage, and means for elevating and lowering the forward end of the lower strip with respect to the wheeled carriage.

5. Apparatus for weaving a strand into a substantially horizontally disposed open-mesh cross-strand fabric comprising a wheeled carriage adapted for movement over said fabric, an elongate strip adapted to assume a substantially horizontal position in close proximity to said fabric, a vertically deflectable extension on one end of said elongate strip, a second elongate strip disposed above and in substantial parallelism with said first-named strip whereby the strand to be woven may be inserted between said strips, the upper strip being disposed to converge upon and engage the inserted strand at a point which is adjacent the deflectable extension on the lower strip, means on said deflectable extension for engagement by the cross-strands of the fabric to impart a weaving motion to said extension during the unitary longitudinal movement of the upper and lower strips with the wheeled carriage, and a shear disposed adjacent said deflectable extension.

6. Apparatus for weaving a strand into a substantially horizontally disposed open-mesh cross-strand fabric comprising a wheeled carriage adapted for movement over said fabric, an elongate strip adapted to assume a substantially horizontal position in close proximity to said fabric, a vertically deflectable extension on one end of said elongate strip, a second elongate strip disposed above and in substantial parallelism with said first-named strip whereby the strand to be woven may be inserted between said strips, the upper strip being disposed to converge upon and engage the inserted strand at a point which is adjacent the deflectable extension on the lower strip, remotely controlled means for effecting the longitudinal sliding movement of the upper strip with respect to the lower strip to thereby feed the forward end of said strand over said deflectable extension, and means on said deflectable extension for engagement by the cross-strands of the fabric to impart a weaving motion to said extension during the unitary longitudinal movement of the upper and lower strips with the wheeled carriage.

JOSEPH E. ARENA.
